UNITED STATES PATENT OFFICE

FRED HAMM, OF MARTINS FERRY, OHIO, ASSIGNOR TO WHEELING BRONZE CASTING COMPANY, A CORPORATION OF WEST VIRGINIA

PICKLING APPARATUS

Application filed November 10, 1930. Serial No. 494,496.

My invention relates to pickling apparatus, particularly to apparatus for pickling metal rods, bars, tubes, pipes, and other elongate things of metal.

5 In pickling it is desirable that the scale, which is invariably present upon the metal to be pickled, may be loosened and removed from all surfaces. It is desirable to subject the de-scaled surfaces to the action of the 10 pickling bath; not only to the chemical action of the bath, but also to a mechanical scrubbing and washing action. It is further desirable that the material to be pickled may be quickly loaded into and unloaded from the 15 pickling apparatus. The object of my invention is to provide means which may be associated with a pickling tank for the accomplishment of these desiderata with particular efficiency.

20 Economy in the installation and operation of the apparatus, and simplicity in its structure are also objects in mind. Other objects will present themselves in the following specification.

25 In the accompanying drawings, forming a part of this specification, Fig. I, is a view in plan from above of a pickling tank which is provided with instrumentalities in accordance with my invention. Fig. II is a view 30 of the apparatus in side elevation. Fig. III is a sectional view taken on the plane III—III of Fig. II, showing in end elevation the pickling tank, and illustrating in detail the mechanical linkages for the handling of the 35 material to be pickled. Figs. IV, V and VI are schematic views of the above mentioned linkages, showing the same in three different stages of their operation. And Fig. VII is a side elevation of the pickling apparatus, 40 showing a modification in the arrangement of the above-mentioned mechanical linkages.

45 My apparatus comprises a tank, conveniently a rectangular tank 1, adapted to retain a pickling bath of acid. A plurality of standards 2 is disposed along each of the sides 10 of the tank, and at their upper termini the standards 2 have each a bearing 3 for revolvably supporting the shafts 4 and 5, which are disposed above the top edges of the tank's 50 sides 10. At one end of the tank, means are

stationed to effect oscillation of these shafts; the character of these oscillations will be hereinafter described, and for the present, only the means for moving the shafts 4 and 5 will be explained. Referring to Figs. I and 55 II it will be noted that an electric motor 6 is coupled to a gear reduction box 7 on a base 8. A shaft 9 extends from the speed-reducing means 7; this shaft is supported by a standard 11, and has secured to its terminus an eccentric or pitman 12. Adjustably secured to each of the shafts 4 and 5 (Fig. III) is an arm (arms 13 and 14 respectively), and pivotally connected at its one end to the arm 13 and at its other end to the pitman 12 is a link 60 15. Two links 16 and 17, which links are pivotally interconnected at 18, serve as a connecting linkage between the pitman 12 and the arm 14. Rotation of the shaft 9 and pitman 12 effects the oscillation of each of 65 the shafts 4 and 5 through a fraction of a revolution, the fraction of a revolution through which the shaft 4 is oscillated being unequal to that through which the shaft 5 is moved.

70 Secured, say by means of set screws 19, to the shaft 4 are several arms 20. These arms 20 extend from the shaft toward the tank and are disposed in spaced intervals along its length, as appears in Fig. I. Affixed to the shaft 5, opposite the arms 20, are arms 21, and each pair of opposed arms 20, 21 carries a cradle member 22. A link 23 affords an articular connection between one leg of the cradle 22 and its associated arm 20, and a 75 link 24 gives a like connection between the other leg of the cradle and its associated arm 21. So, each opposed pair of arms 20, 21 together with their associated links 23, 24, suspends a cradle member—conveniently, a separate, rigid U shaped cradle member 22. The manner in which these cradles 22 move in response to the oscillations of the shafts 4 and 80 5 is a matter of importance to the effective working and shifting of the material which 85 is within the tank for pickling.

90 In Figs. III to VI inclusive, I indicate in end elevation a group G of metallic rounds within the tank 1 for pickling. When the rounds (or other stock to be pickled) are first 95 100

placed into the tank, the cradles and their associated linkages are desirably, although not necessarily, in the position in which they are indicated in Fig. III. Manifestly, access is thereby had for the ready immersion of the stock below the surface of the pickling bath; such surface of the bath is indicated by the broken line B.

Within the bath, the stock is not continuously supported by the cradles 22; indeed, when the cradles are in their lowermost position (Fig. III), the stock is borne by auxiliary means which advantageously comprise several supports 25. The supports 25 are secured at their ends to the opposite sides 10 of the tank 1; they are shaped to converge downward, and in their lower portions they are of angular form; that is to say, the supports 25 are each W-shaped to provide two "pockets" 26 and 27. As may be seen in Figs. I and II, one support 25 is (conveniently) located adjacent each cradle 22, and the stock to be pickled rests upon these supports when the cradles 22 are in their lowermost position (Fig. III).

To better understand the operation of the apparatus, I shall describe what takes place during one revolution of the shaft 9, assuming for illustration that the shaft revolves counter clockwise in Figs. III to VI. At the start of this illustrative revolution the pitman 12 and its associated links, the shafts 4 and 5 with their arms 20 and 21, the links 23 and 24, and the cradles 22 are in the position shown in Fig. III. In such position it will be noted that the group G of material to be pickled rests upon the fixed supports 25 and below the surface B of the bath. As the shaft 9 moves from the position in which it is shown in Fig. III, the shaft 4, by means of the arm 13 and link 15, is revolved counter clockwise, the arms 20 are moved upward, and the cradles 22 are, accordingly, raised and tilted to the position shown in Fig. IV.

During this movement of the mechanical elements which are recited above, the cradles 22 rise against the stock G, and lift it. Because of the tilting of the cradles 22 the bars of stock to the left in the group G are raised higher than those to the right. Such a raising and tilting causes a left-to-right shifting of the bars, as indicated by the arrows in Fig. IV. In this shifting the bars roll upon themselves and rub their surfaces against one another. The bars in the upper courses of the group G are caused to roll rather freely toward the right, and in so rolling they eventually come with considerable impact against others of their fellow bars. This impact of the bars against one another, as well as their rolling and abrading against each other, is of great advantage in effecting the removal of surface scale. Particularly in the case of pickling tubes is the "impact" feature advantageous, in that the removal of

scale on the inner walls of the tubes (which removal of scale has always been quite difficult) is greatly facilitated.

Continuing rotation of the shaft 9, to the position indicated in Fig. V, further revolves the shaft 4 counter clockwise, and in this particular stage of the rotation of shaft 9, the shaft 5, which (due to the character of the connecting members 16, 17 and 14) has until now moved only slightly, is moved appreciably in clockwise rotation. Consequently, the cradles 22 are so raised that none of the bars rest upon the supports 25; the tilting of the cradles is increased to a greater degree, and the combined raising and tilting of the bars is accomplished to such an extent that some of the bars are lifted above the surface B of the acid. It is to be remarked that the lifting of the bars out of the bath is an important feature of my invention.

In so raising the stock which is being pickled above the bath, much of the acid in immediate contact with the surfaces of the stock falls away, and, as a result, the stock is subjected to the air and acid fumes existing over the bath. The chemical activity in pickling, accordingly, has been found to be improved and quickened; and, when the stock is again lowered into the bath, as it indeed is lowered, fresh acid, so to speak, comes into active contact with surfaces of the stock. The rolling and bumping of the bars upon themselves continues, while the stock continues its shifting in the manner indicated by the arrows in Fig. V.

As the shaft 9 and its associated linkages turn toward the positions in which they are shown in Fig. VI, the cradles 22 are lowered and their inclination, as they so lower, is lessened. The group G of bars settles again within the bath of acid, while as a group the bars tend to flatten out in the manner indicated by the arrows. Continued rotation moves the mechanism back into the position in which it is illustrated in Fig. III, and the group of bars again settle upon the supports 25. When the cradles lower into approximately such position as to deposit the stock once again upon the supports 25, they (the cradles) shift abruptly in a right-to-left direction, as indicated by the arrow which is applied immediately to the cradle 22 in Fig. VI. This shifting of the cradles tends evenly to distribute the stock transversely of the supports 25, as it is shown to be distributed in Fig. III. Although it does not conspicuously appear in the drawings, the link 24 is slightly longer—a few inches—than the link 23, and this difference in the lengths of these two links, together with the characteristics of the other links of the mechanism, furthers the operation of the device as described.

To give a general idea of how the bars shift and roll, I have shaded (by cross-hatching)

the end of one bar, and in noting the position of this shaded bar in each of Figs. III to VI, the travel or movement of each bar, and of the group, during continuous rotation of the 5 shaft 9, may be realized. In brief, the bars are caused severally to rotate about their own axes, while they tumble upon themselves, and as a group revolve.

I have discovered that the apparatus may 10 be elaborated to obtain an advantage which is of particular merit in the pickling of tubes. The elaboration also, as a matter of fact, finds applicability in the pickling of solid rods and bars.

15 Instead of having the lower, bar-supporting portions of cradles 22 extending in such manner as to sustain the bars, as a group, in a horizontal plane, the several pairs (20, 21) of arms may be so adjusted (by means of the 20 set screws 19) on their respective shafts 4 and 5 that the cradles 22 will carry the tubes, which are being pickled, at an angle to the horizontal. That is, the tubes when lifted by the cradles may be caused to assume an 25 inclination, such as is indicated by the line A in Fig. VII. For that matter the supports 25 may each be so dimensioned with respect to their height as to cause the tubes to rest in an inclined position when the cradles are 30 in their lowermost position—the position in which they do not support the tubes. However, such arrangement of the supports 25 is not always essential; the important thing 35 being that the tubes, as they are shifted in the bath and particularly when they are raised above the bath, to the position indicated by the line C in Fig. VII, shall be inclined to the horizontal. The ensuing advantage of 40 this disposition of the tubes is that acid is caused to gravitate through the tubes. The gravitation or flowing of acid within the tubes is most marked, of course, when the tubes are lifted above the bath; it is then that the acid 45 flows rapidly, carrying with it the scale which has been loosened on the inner walls of the tubes. This mechanical cleansing of the interiors of the tubes is very desirable. Other attending advantages are that air reaches the 50 inner surfaces of the tubes and hastens the chemical cleansing action, and that so-called new acid is brought into contact with the inner, as well as the outer walls of the tubes when they are again immersed.

55 My apparatus is more effective in removing scale, it performs the pickling operation in less time, and in general is more efficient than pickling devices now in use.

I claim as my invention:

60 1. The method of pickling a group of elongate things of metal, which comprises the steps of immersing the group in a pickling bath, alternately raising, lowering and tilting the group within said bath, thus causing the members of the group to rotate severally 65 about their longitudinal axes and to tumble

against one another, by revolving the group as a whole progressively upon itself.

2. The method of pickling a group of elongate things of metal, which comprises the 70 steps of longitudinally inclining the group in a pickling bath, alternately raising, lowering and laterally tilting the group while it is in such inclined position in said bath, thus causing the members of the group to rotate severally about their longitudinal axes and to tumble against one another, by causing the 75 group to roll progressively upon itself, and periodically raising members of such inclined group to a position above the surface of said bath.

3. In combination with a tank containing 80 a bath of pickling fluid, a plurality of rigid, spaced cradles in said tank for the support of the material to be pickled, and means to effect a series of movements of the cradles within the tank, which movements comprise an alternate raising and lowering of the cradles, wherein one end of each cradle during each of the raising movements is raised 85 a greater distance than its other end.

4. In combination with a tank containing 90 a bath of pickling fluid, a plurality of cradles in said tank for the support of material to be pickled, which cradles are as a combined body longitudinally inclined to the horizontal, and means to effect a series of movements of the cradles within the tank, which movements comprise an alternate raising and lowering of the cradles, the one end of each cradle during its raising movement being 95 raised a greater distance than its other end.

5. In combination with a tank containing 100 a bath of pickling fluid, stationary means for the support of the material to be pickled, said stationary means including irregular 105 material-supporting faces, as described; and movable supports, together with means for moving said movable supports to effect a raising of said material from said stationary supporting means and to effect agitation of said material and to replace it upon said stationary supporting means.

6. In combination with a tank containing 110 a bath of pickling fluid, a set of supports having irregular faces for sustaining a group of bars within a pickling bath, a second set of supports, and means for effecting a raising, lowering and tilting of said second set of supports, whereby said bars are periodically lifted from said first-mentioned supporting 115 means and revolved, severally, and as a group, and then returned to said irregular faces of said first-mentioned supports.

7. In combination with a tank containing 120 a bath of pickling fluid, a set of supports for the material to be pickled, a second set of supports, and means for effecting a combined bodily raising, lowering and tilting of said second set of supports, whereby said material 125 is periodically lifted from said first-men-

tioned supports, and then agitated and returned to rest upon said first-mentioned set of supports.

8. The method of pickling a group of elongate things of metal, which comprises the steps of immersing the group in a pickling bath, alternately raising the group from a support, tilting the group, and returning the group to a position upon the support, thus causing the members of the group to rotate severally about their longitudinal axis and to jar against one another, by revolving the group as a whole.

9. The method of pickling a group of elongate things of metal, which comprises the steps of immersing the group in a pickling bath, alternately raising the group from a support, tilting the group, and returning the group to a position upon the support, thus causing the members of the group to rotate severally about their longitudinal axis and to jar against one another, by revolving the group as a whole, and, as the group is so raised and revolved, effecting a shifting of certain members of such group to a position above the surface of said pickling bath.

In testimony whereof I have hereunto set my hand.

FRED HAMM.
